(57) **CLAIM**

The ornamental design for a portion of a rack for an object such as a gun, bow, or tool, as shown and described.

DESCRIPTION

FIG. 1 is a perspective view of a portion of a rack for an object such as a gun, bow, or tool showing my new design according to a first embodiment;

FIG. 2 is a front elevational view of the first embodiment;

FIG. 3 is a rear elevational view of the first embodiment;

FIG. 4 is a right side elevational view of the first embodiment;

FIG. 5 is a left side elevational view of the first embodiment;

FIG. 6 is a top plan view of the first embodiment;

FIG. 7 is a bottom plan view of the first embodiment; and,

FIG. 8 is a front elevational view of a portion of a rack for an object such as a gun, bow, or tool showing my new design according to a second embodiment, the second embodiment being identical to the first embodiment except that no portion of the article between the break lines forms any part of the claimed design.

The broken lines in FIGS. 1-8 form no part of the claimed design.

1 Claim, 4 Drawing Sheets
